FIRE DETECTION SYSTEM

Francis C. Evans, Dongan Hills, N. Y., assignor to
 American District Telegraph Company, Jersey
 City, N. J., a corporation of New Jersey

Application November 22, 1940, Serial No. 366,514

6 Claims. (Cl. 200—143)

This invention relates generally to fire detection systems and more particularly to systems adapted for detecting fire in structures such as railway bridges, round houses, or any other wooden structures which are so located that they are normally not supervised and are subject to unusual temperature conditions or fire hazards.

All railroad bridges, even those the main supporting structure of which is steel, include wooden ties for supporting the track and wooden tie supports. Because of the characteristics of the preservatives customarily used in railroad ties or other wooden supporting structure, the fire hazard is unusually great, since steam locomotives discharge hot coals on the track bed and electric locomotives frequently ignite ties because of electric sparks from third rails or sparks from the rails resulting from application of the brakes. In the case of steam locomotives, the discharge of ashes or hot coals results in an accumulation of inflammable materials on the ties and their supports whereby a fire may be started if and when favorable conditions occur. When fires start on isolated bridges or trestles, they frequently gain considerable headway before being discovered and after discovery it is usually impossible to reach the fire with fire extinguishing equipment sufficient to control a large fire. Thus, it is extremely important to detect fire conditions in railway structures for the purpose of notifying the proper authorities and facilitating control of the fire before it has reached dangerous proportions.

Fire detection on railway structures is a difficult problem for the reason that the track and a sizable proportion of its support is subject to extreme ranges of temperature both from the effects of the sun and from standing locomotives. It has been found that the temperature under the fire box of a standing locomotive may rise very rapidly to as high as 210° F. This change of temperature occurs along or between the tracks at the very point where fire is most likely to occur, thereby rendering the selection of detecting apparatus very difficult. Rate of rise equipment is not suitable since temperature changes occur at rapid rates. The usual form of fixed temperature thermostats are also not suitable, since they do not afford continuous supervision over extended distances or areas in outdoor locations such as those of railway bridges.

Railway structures also render fire detection extremely difficult because of vibration resulting from passing trains, vibration of the track and ties frequently involving amplitudes up to two

inches. This necessitates the use of a fire detecting element which can be supported in such a manner that it is not flexed to the extent that crystallization will cause failure or change in operating temperature. A further difficulty arises due to physical blows resulting from falling objects or the passage of track walkers.

Accordingly, the principal object of this invention is to provide a fire detection system for use in railway structures.

A further object of this invention is to provide a fire detector capable of supervising fire conditions on railway structure where continuous supervision over substantial distances is necessary.

Another object of this invention is to provide a fire detector capable of withstanding extreme distortion resulting from vibration.

Still another object of this invention is to provide a fire detector for detecting fire conditions on outdoor structures in spite of temperature changes of extreme latitude and high rates.

A still further object of this invention is to provide a fire detection system adapted for use on railway structures.

A still further object of this invention is to provide an adequately supervised signaling system for use in connection with fire detection apparatus which is capable of withstanding extreme amplitude of vibration and affording continuous fire supervision over long distances under outdoor conditions.

Further objects and advantages of the invention will be apparent to those skilled in the art after consideration of the following specification taken in connection with the accompanying drawings, wherein:

Fig. 1 is a plan view of a section of railway bridge together with the track and fire detecting equipment;

Fig. 2 is a cross section of Fig. 1 taken on line 2—2;

Fig. 3 is a perspective view illustrating the construction of the fire detecting equipment; and

Fig. 4 is a circuit diagram illustrating the connections of signaling equipment to the fire detecting equipment shown in Fig. 1.

Figs. 1 and 2 illustrate a fire detector supported on a bridge in accordance with the preferred form of the invention. The bridge structure is typical of railway bridge construction and is shown by way of example only. The track support rests upon steel members 1 which may be secured to the remainder of the bridge in any desired fashion. Longitudinal steel members 2 are supported by

the structure 1 and they in turn carry a plurality of lateral track supporting beams 3. The ties 5 which support rails 1 are fastened to longitudinal wooden beams 8. The construction is further typical of all bridge construction in that guard rails 9 are provided for safety purposes. Many bridges also include a walk 11 on one side of the track and also longitudinal wooden beams 12.

From the above description it is apparent that even steel bridges include inflammable materials, and the occurrence of fire not only causes destruction of the ties 5 but also of the longitudinal members 8 together with the steel supports 1, 2 and 3. The longitudinal supports 8 collect ashes and coals between the ties 5 as shown in Figs. 1 and 2 at 10, this particular part of the bridge structure being that which is most likely to become ignited from passing locomotives.

In view of the fact that the origin and occurrence of fires can be substantially localized to the longitudinal wooden supports 8, it is essential that the fire detector be located as near as possible to this area where fires have been found most likely to start. This area is also important for the reason that the fire should be detected before serious damage is done to the ties and rails. Detectors 15 are preferably placed between the track rails 7 and the guard rails 9, as illustrated in Figs. 1 and 2. It will be obvious that the fire detectors 15 may be located at the outside of the rails 7 or a third fire detector may be provided if the peculiarities of the particular bridge in question so require. It is to be noted that this form of fire detector affords continuous supervision of a bridge whereby the entire length of track is protected. Other forms of fixed temperature fire detectors necessarily leave unprotected areas when used in outdoor structures such as bridges.

As illustrated in Figs. 1 and 2, the occurrence of a fire between the ties 5 will immediately cause the detectors 15 to operate, and in addition, if burning cigarettes or other materials cause a fire to start in the walkway 11 or in any other part of the structure, the detector 15 will eventually be operated from spread of the fire along the vertical surfaces of the ties 5, these surfaces being the initial ones to become ignited.

Fig. 3 illustrates the construction of the fire detector 15 which comprises fire detecting conductors 17, molding 20, and flexible insulating compound 23. The fire detecting wire 17 consists of a fusible material which should preferably melt at a temperature in the neighborhood of 400° F. whereby a safe margin over the melting temperature of the insulating compound 23 is obtained. The insulating compound 23 is preferably selected to have a melting temperature in the neighborhood of 250° to 275° F. which gives a safe margin over the maximum ambient temperatures occurring under standing locomotives, this temperature being approximately 210° F. The fire detecting wire 17 has a rosin core 18 which vaporizes to allow an actual break in the wire to occur more readily when the fusing temperature is reached. If the wire were solid, it would probably melt in such a way that the circuit would not be broken, the wire merely losing its form.

The molding 15 and the detecting wire supported thereby extends longitudinally along the track, as illustrated in Fig. 1, and is supported by means of the brackets 22, the brackets 22 being of such dimensions that molding 15 fits very loosely therein. It has been found that vibration occurring upon the passage of heavy trains may cause an amplitude of the order of two inches in

vibration of the molding 20, and therefore this element is constructed of wood. Pipe or other metallic materials are sometimes subject to crystallization as a result of the vibration and, therefore, are useful in very few instances. Since the molding 20 fits loosely within the bracket 22, the passage of heavy trains does not cause excessive flexing of the molding and does not subject the fire detecting wire 17 to high frequency vibration or stretching, thereby preventing change of fusing temperature, false alarms or other troubles.

Upon the occurrence of a fire the insulating compound 23 is melted at temperatures of 250° to 275° F., whereupon the fire detecting wire 17 becomes exposed to air temperatures. If the temperature continues to rise, the wire 17 melts at approximately 400° F., thereby breaking the alarm circuit to initiate a fire alarm.

The alarm circuit is illustrated in Fig. 4 of the drawings and comprises two parallel runs of fire detecting wire 17. To explain further, between the rails of each track there are two runs of the fire detector 15, each including two fire detecting conductors 17. These conductors are connected together at their mid-point, usually at one end of the bridge, by means of resistances 25 and are connected across the battery 27 in parallel through resistances 28 at one side of battery 27 and through the coil of trouble relay 30 at the other side of battery 27. Relay 30 is differentially wound and, therefore, normally deenergized, maintaining the circuit of trouble alarm bell 31 open. Relay 30 is connected at the mid-point of its coil to the normally energized slow-acting alarm relay 33 and normally open reset push button 35. The alarm relay 36 is connected across battery 27 through contact 38 of relay 33, and normally open push button 35 is normally shunted by contact 39 of relay 33. Alarm 40 is connected through a battery to the normally open contacts of relay 36, and this circuit may also operate the block signals of the railway signaling circuit.

It will be obvious from the drawings that the occurrence of fire melts the insulating compound 23 and both of the fusible conductors 17. Relay 30 being differentially wound, a break in both conductors of the detection circuit has no effect on alarm 31, and relay 33 becomes deenergized and opens its contacts 38 and 39. Relay 36 thereupon becomes deenergized and operates the alarm 40, and in addition it may also operate train signals in the block signaling system.

When the fire condition has been controlled and the ruptured conductors 17 repaired, the circuit is restored to normal by closing the alarm circuit at push button 35, thereby reenergizing relay 33 and closing contacts 38, 39 to reenergize relay 36.

If the alarm circuit should become grounded between one of the conductors 17 and ground, there would be no false alarm, since the entire circuit is not grounded. Therefore, no trouble signal for this condition is necessary. If two grounds in one of the conductors 17 should occur on the same side of resistor 25, there would still be no false alarm and no trouble signal. If two simultaneous grounds occur, one on each side of resistor 25, this resistor becomes short-circuited and current in one detector wire becomes greater than that in the other, causing an unbalance in relay 30 which closes the trouble circuit through alarm 31. However, since relay 30 is differentially wound, the alarm circuit remains

closed, and alarm relay 33 is not operated. If a short circuit occurs between the conductors 17, there is no change in current flowing through relay 33, and therefore no false alarm results. It will be obvious that the circuit can always operate to cause an alarm when the fire detecting conductors simultaneously fuse and break the alarm circuit. This is true except in the case where the fire occurs between two grounds existing on a single conductor, in which case the other conductor melts and relay 30 becomes unbalanced to initiate a trouble signal.

It will be obvious that any form of fire detecting wire may be used so long as it operates at a temperature above the safe ambient temperatures which normally occur along the railroad track. It is preferred, however, that a rosin core wire consisting of an alloy composition of lead, tin, antimony, and bismuth be used. Any form of insulating compound 23 is suitable so long as it remains flexible under ambient temperatures and melts at approximately 275° F. This material preferably consists of a rubber content mastic which never becomes brittle under ordinary atmospheric conditions.

The bridge structure illustrated in the drawings is shown by way of example only, the invention being applicable to all types of bridges or other wooden and steel structures such as round houses or road beds. Therefore, the invention should not be limited to the particular construction illustrated in the drawings. Any form of bracket is suitable for supporting the molding 20 so long as it is so constructed that the molding will have a sufficient degree of movement to prevent rupture of the molding or conductors 17 or crystallization of the conductors.

From the above description it is evident that this invention provides a fire detection system which is particularly adapted for use in connection with railway track supporting structures. The system is not affected by normal ambient temperatures occurring along the road bed, and it is not affected by physical impact from falling objects or other causes. Furthermore, the particular form of fire detector continuously supervises any desired length of track together with its supporting structure, whereby fire may be detected in the inherently inaccessible areas which are characteristic of railroad bridges. Detection occurs before serious fire conditions can arise whereby simple forms of fire extinguishing equipment are adequate to extinguish the fire. The particular form of detector and its supporting bracket eliminates injuries resulting from the excessive vibrations caused by the passage of heavy high speed trains.

It is not intended that the invention shall be limited to the form illustrated in the drawings, since various modifications will be obvious to those skilled in the art, and therefore it is desired that the invention shall be limited only by the appended claims as required by the scope of the prior art.

I claim:

1. The combination with inflammable supporting structure subject to vibration of a fire detector comprising runs of wood molding, a pair of fusible electrical conductors within each run

of said molding, the conductors being connected to one another, and brackets on the inflammable supporting structure surrounding said molding for attaching the molding to said structure against separation therefrom and for loosely supporting the molding whereby vibration does not cause excessive flexing of the molding and conductors.

2. The combination with inflammable supporting structure subject to vibration of a fire detector comprising two substantially parallel runs of wood molding, a fusible electrical conductor within each run of said molding, the conductors being connected to one another, and brackets on the inflammable supporting structure surrounding said molding for attaching the molding to said structure against separation therefrom and for loosely supporting the molding whereby vibration does not cause excessive flexing of the molding and conductors.

3. The combination with inflammable supporting structure subject to vibration of a fire detector comprising a run of wood molding, a fusible electrical conductor within said molding, and brackets on the inflammable supporting structure surrounding said molding for attaching the molding to said structure against separation therefrom and for loosely supporting the molding whereby vibration does not cause excessive flexing of the molding and conductors.

4. A fire detecting device for affording continuous supervision of fire conditions along its length comprising a wood molding, a fusible electrical conductor within a groove in said molding, and sealing means for protecting said fusible electrical conductor from the effect of temperature changes and mechanical shock including a flexible material in said groove which is fusible at a lower temperature than said conductor whereby the occurrence of a predetermined temperature in the vicinity of said molding melts the sealing means and exposes said fusible conductor to the dangerous temperature.

5. A fire detecting device for affording continuous supervision of fire conditions along its length comprising a flexible molding, a fusible electrical conductor within said molding, and sealing means for protecting said fusible electrical conductor from the effects of temperature changes and mechanical shock including a plastic material which is fusible at a lower temperature than said conductor whereby the occurrence of the predetermined temperature in the vicinity of said molding melts the sealing means and exposes said fusible conductor to a dangerous temperature.

6. A fire detecting device for affording continuous supervision of fire conditions along its length comprising a support, a fusible electrical conductor within said support, and sealing means for protecting said fusible electrical conductor from the effects of temperature changes and mechanical shock including a material which is fusible at a lower temperature than said conductor whereby the occurrence of the predetermined temperature in the vicinity of said support melts the sealing means and exposes said fusible conductor to a dangerous temperature.

FRANCIS C. EVANS.
